PENCIL AND PEN CLIP

Clinton E. Marshall, New York, N. Y.

Application October 30, 1937, Serial No. 171,843

10 Claims. (Cl. 24—11)

This invention relates to clips designed for use in connection with fountain pens and other writing implements for retaining the same against displacement from a pocket or other support as in other devices of this kind; and the object of the invention is to provide a simple and economical form of clip construction involving a relatively rigid clip body forming one part of the device and a spring part forming means for coupling the first named part to its support and for tensionally holding the first named part in operative position upon the support; a further object being to provide a spring part having at one end thereof a T-shaped cross-head forming the coupling means for said clip part, said spring part being recessed adjacent the cross-head facilitating attachment of the clip part therewith to provide a simple and yet strong and durable coupling between said parts; and with these and other objects in view, the invention consists in a device of the class and for the purpose specified, which is simple in construction, efficient in use, and which is constructed as hereinafter described and claimed.

25 The invention is fully disclosed in the following specification, of which the accompanying drawing forms a part, in which the separate parts of my improvement are designated by suitable reference characters in each of the views, and in which:

30 Fig. 1 is a side and sectional view of a part of a fountain pen showing one of my improved clip devices arranged thereon.

Fig. 2 is a face view of the construction shown in Fig. 1 with part of the construction broken 35 away and in section.

Fig. 3 is a longitudinal sectional view through the clip device detached.

Fig. 4 is a perspective view of the spring part of the device which I employ, detached.

40 Fig. 5 is a partial section on the line 5—5 of Fig. 1 on an enlarged scale; and,

Fig. 6 is a view similar to Fig. 5 on an enlarged scale, and showing a modification.

To illustrate one method of carrying my invention into effect, I have shown in Figs. 1 and 2 of the drawing at 10, the cap of a fountain pen having a removable plug or head 11 at one end thereof for supporting one of my improved clips 12 in connection with the cap. In the construction shown, the plug 11 has a reduced threaded portion 13 engaging a correspondingly threaded bore of the cap 10; this construction forming a shoulder 14 for engaging the ring end 15 of a spring part 16 of the clip. This part has a spring arm 17 depending from one peripheral edge of the ring

15, note Fig. 4, and the arm terminates at its free end in a cross-head or coupling portion 18 which forms projecting flanges 19 and 20 at each side of the arm which extend outwardly beyond the side edges 21 of said arm.

One of the edges 21 adjacent the head 18 has a deep recess 22 which as shown is disposed adjacent the flange 20, to provide means for coupling the part 16 with the clip part proper 23. The part 23 consists of an elongated member of channel cross-sectional form; that is to say, the member is provided with a top wall 24 and depending side walls 25 which project at the upper end of the clip to form rounded pivot or bearing ends 26 and project at the other free end of the clip to register with an inturned bearing part 27, similar to the conventional ball end usually provided in devices of this kind; this structure facilitating free insertion and removal of a pocket wall or other support between the part 27 and the cap 10.

The upper end of the clip is also provided with a downwardly turned top wall 28 which closes and conceals the top of the clip so as to render the spring part 16 substantially invisible as will be apparent.

The side walls 25 adjacent the top wall 24 are provided with apertures 29, 29a, at a point slightly nearer the end of the clip provided with the projection 27, in which apertures, the projecting flanges 19, 20, respectively, are adapted to be placed in coupling the parts 16 and 23. It will be noted that the outer ends of the flanges 19 and 20 rest in a plane flush with the outer surfaces of the side walls 25 as will appear upon a consideration of Fig. 2 of the drawing.

In the operation of coupling the parts 16 and 23, the spring arm 17 is flexed in the manner indicated partially in dotted lines in Fig. 3 of the drawing; and the member 20 is first passed through the aperture 29a, the recess 22 clearing the adjacent side wall 25 of the clip in this operation. Then the flange 19 is placed in the aperture 29 by moving the cross-head 18 transversely as will be apparent: When the flange 19 is in position, the entire arm 17 is free to pass into the channel of the clip 23 and is made to fit snugly therein; that is to say; the side edges 21 will fit snugly within the walls 25 so as to support the clip 23 against any possible movement with respect to the arm. If desired this assemblage may be accomplished under pressure to insure firm engagement of the parts.

In Fig. 6 of the drawing, I have shown a modification which simply consists in beading the side walls 25a of the clip as seen at 30, 30a,

to form recesses 31, 31a, in which the projecting flanges 19 and 20 may be passed. However, with this construction, the cross-head 18 will be flexed transversely by suitable tools in making the assemblage, the recess 22 in this connection permitting the flexure of the cross-head, and especially in the long flange 20 thereof. This method of assemblage may also be used in connection with the structure shown in the other figures as will be apparent.

It will appear that the part 23 constitutes the clip body proper and by virtue of its channel construction, this clip forms a hood which conceals the exposed portion of the part 16, and especially the arm 17 thereof, with the exception of where the ends 19, 20, are exposed through the body as in Figs. 1 to 5 inclusive. However, in Fig. 6, the arm is completely concealed.

It will also appear that by virtue of the snug mounting of the arm 17 within the channel of the body 23, the two parts become as one with no relative movement with respect to each other. The spring arm normally supports the rounded projection 27 in tensional engagement with the surface of the cap 10.

Having fully described my invention, what I claim as new and desire to secure by Letters Patent, is:

1. In clips of the class described, a spring part for coupling a clip body in connection with a suitable support, said part comprising an elongated spring arm, means at one end of the arm for attaching the same to a support, the other end of the arm having laterally projecting coupling flanges, and said arm adjacent one of said flanges being recessed to facilitate attachment of a clip body with the flanges of said arm.

2. A clip for mounting writing implements in connection with suitable supports, said clip comprising an elongated clip body of channel cross-sectional form to provide an outer wall and depending side walls on said body substantially throughout the length thereof, means forming a rounded knob or head at one end of said body, the side walls of said body having recesses substantially centrally of said body, a spring arm arranged in the channel of said body, said arm having projecting members located in the recesses in the side walls of said body to retain said body against longitudinal movement on said arm, and means on said arm for securing the clip to a writing implement in such manner as to support the knob end of said body in tensional engagement with the outer surface of said implement.

3. A clip for mounting writing implements in connection with suitable supports, said clip comprising an elongated clip body of channel cross-sectional form to provide an outer wall and depending side walls on said body substantially throughout the length thereof, means forming a rounded knob or head at one end of said body, the side walls of said body having recesses substantially centrally of said body, a spring arm arranged in the channel of said body, said arm having projecting members located in the recesses in the side walls of said body to retain said body against longitudinal movement on said arm, means on said arm for securing the clip to a writing implement in such manner as to support the knob end of said body in tensional engagement with the outer surface of said implement, and said spring arm fitting snugly in and arranged longitudinally of the channel of

said body to retain the body against lateral movement on said arm.

4. A clip for mounting writing implements in connection with suitable supports, said clip comprising an elongated clip body of channel cross-sectional form to provide an outer wall and depending side walls on said body substantially throughout the length thereof, means forming a rounded knob or head at one end of said body, the side walls of said body having recesses substantially centrally of said body, a spring arm arranged in the channel of said body, said arm having projecting members located in the recesses in the side walls of said body to retain said body against longitudinal movement on said arm, means on said arm for securing the clip to a writing implement in such manner as to support the knob end of said body in tensional engagement with the outer surface of said implement, said spring arm fitting snugly in and arranged longitudinally of the channel of said body to retain the body against lateral movement on said arm, and said arm being recessed adjacent one of said projecting members to facilitate the coupling of said arm with said clip body.

5. A clip of the class described comprising a spring part and a clip body detachably coupled therewith, said spring part comprising an elongated arm, means on one end of the arm for mounting the same in connection with a support for securing the clip against displacement from the support, said clip being of channel cross-sectional form throughout the length thereof to provide spaced side walls, said body being arranged longitudinally of and covering said arm, laterally projecting means on the other end portion of said arm, and the side walls of said channel having recesses receiving said projecting means for coupling said body to the arm to retain the same against displacement therefrom.

6. A clip of the class described comprising a spring part and a clip body detachably coupled therewith, said spring part comprising an elongated arm, means on one end of the arm for mounting the same in connection with a support for securing the clip against displacement from the support, said clip being of channel cross-sectional form throughout the length thereof to provide spaced side walls, said body being arranged longitudinally of and covering said arm, laterally projecting means on the other end portion of said arm, the side walls of said channel having recesses receiving said projecting means for coupling said body to the arm to retain the same against displacement therefrom, and the side edges of said arm fitting snugly within the side walls of said channel to retain the body against lateral movement on said arm.

7. A clip of the class described comprising a spring part and a clip body detachably coupled therewith, said spring part comprising an elongated arm, means on one end of the arm for mounting the same in connection with a support for securing the clip against displacement from the support, said clip being of channel cross-sectional form throughout the length thereof to provide spaced side walls, said body being arranged longitudinally of and covering said arm, laterally projecting means on the other end portion of said arm, the side walls of said channel having recesses receiving said projecting means for coupling said body to the arm to retain the same against displacement therefrom, the side edges of said arm fitting snugly within

the side walls of said channel to retain the body against lateral movement on said arm, the free end of said clip having a rounded knob normally held in engagement with the surface of the support in connection with which the clip is mounted by said spring part, and the other end of said body having rounded projections engaging the surface of the support to form a pivot upon which said body is free to swing outwardly with respect to the support.

8. A clip of the class described comprising a spring part and a clip body detachably coupled therewith, said spring part comprising an elongated arm, means on one end of the arm for mounting the same in connection with a support for securing the clip against displacement from the support, said clip being of channel cross-sectional form throughout the length thereof to provide spaced side walls, said body being arranged longitudinally of and covering said arm, laterally projecting means on the other end portion of said arm, the side walls of said channel having recesses receiving said projecting means for coupling said body to the arm to retain the same against displacement therefrom, and the said side walls at the upper end of the clip body having rounded projections engaging the surface of the support whereby said body is free to swing outwardly with respect to said support.

9. A clip of the class described comprising a spring part and a clip body detachably coupled therewith, said spring part comprising an elongated arm, means at one end of the arm for mounting the same in connection with a sup-

port and for securing the clip against displacement therefrom, said clip body being of channel cross-sectional form throughout its length to provide spaced side walls and having recesses in said side walls intermediate the ends thereof, said body being arranged longitudinally of and covering said arm, the other end of said arm having side projections forming a T-shaped head, said projections being of equal transverse length with respect to said arm, the sides of said arm 10 throughout its length closely engaging the side walls of said body preventing lateral movement thereof, and the side projections of said T-shaped head being located in the recesses in the side walls of said body preventing longitudinal movement thereof. 15

10. In clips of the class described a spring part for coupling a clip body in connection with a suitable support, said body having depending side walls and apertures in said walls intermediate 20 the ends of said body, said part comprising an elongated spring arm, means at one end of the arm for attaching the same to a support, the other end of the arm having side projections forming a T-shaped head, said side projections 25 being of equal transverse length with respect to the arm, one side of the arm adjacent said head having a recess therein slightly deeper than the length of one of said projections and of a length greater than the depth of one side wall of said body adjacent the aperture therein whereby the projections on the T-shaped head may be coupled with the apertures by the fixture and lateral movement of said arm. 30
